US00D901552S

(12) **United States Design Patent** (10) **Patent No.:** **US D901,552 S**
(45) **Date of Patent:** **** Nov. 10, 2020**

(54) **BUCKET SHROUD**

- (71) Applicant: **Caterpillar Inc.**, Peoria, IL (US)
(72) Inventors: **Nathan Bjerke**, Peoria, IL (US);
Thomas Marshall Congdon, Dunlap,
IL (US)
(73) Assignee: **Caterpillar Inc.**, Peoria, IL (US)
(***) Term: **15 Years**
(21) Appl. No.: **29/724,400**
(22) Filed: **Feb. 14, 2020**

Related U.S. Application Data

- (63) Continuation of application No. 29/669,677, filed on
Nov. 9, 2018, now Pat. No. Des. 882,646.

CLAIM

The ornamental design for a bucket shroud, as shown and described.

DESCRIPTION

FIG. 1 is a front perspective view of a bucket shroud showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate structure or features which form no part of the claimed design.

The dot-dash broken lines illustrate boundaries which form no part of the claimed design.

The drawings include surface shading which represents contour and not surface ornamentation.

1 Claim, 6 Drawing Sheets
